UNITED STATES PATENT OFFICE

148,506

DESIGN FOR A LUNCHEON TABLE

David H. Weinberg, Philadelphia, Pa., assignor to Fountain Server Co., Inc., Philadelphia, Pa.,
a corporation of Pennsylvania

Application May 2, 1946, Serial No. 129,230

Term of patent 7 years

(Cl. D33—14)

To all whom it may concern:

Be it known that I, David H. Weinberg, a citizen of the United States, residing at Philadelphia, in the county of Philadelphia and State of Pennsylvania, have invented a new, original, and ornamental Design for a Luncheon Table, of which the following is a specification, reference being had to the accompanying drawing, forming part thereof.

The figure is a perspective view of a luncheon table, showing my new design.

I claim:

The ornamental design for a luncheon table, as shown.

DAVID H. WEINBERG.
